(57) **CLAIM**

The ornamental design for a windshield wiper blade as shown and described.

DESCRIPTION

FIG. 1 is a front isometric view of a windshield wiper blade showing my new design;

FIG. 2 is a rear isometric view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof; and,

FIG. 8 is a front cross-sectional view along cross-section line 8-8 of FIG. 2 thereof.

The portion of the windshield wiper blade depicted in the figures in broken lines forms no part of the claimed design. The broken lines showing a windshield wiper in FIGS. 3, 4 and 6 are for the purpose of illustrating where the windshield wiper blade is attached to the windshield wiper and forms no part of the claimed design.
